UNITED STATES PATENT OFFICE.

JULIUS SCHÜRMANN, OF BERLIN-ZEHLENDORF, GERMANY.

ELECTRIC FUSE.

Application filed November 2, 1926, Serial No. 145,792, and in Germany February 24, 1925.

My invention relates to electric fuses and more particularly to those used in mines for blasting, in the manufacture of which it has heretofore been usual to employ to a considerable extent a plastic or viscous substance which subsequently hardens and secures the parts together. This substance is largely employed not only to form the parts of the fuse proper into an easily handled article or fuse body, but also to secure this fuse body in the fuse casing or in the detonator shell—according to the type of fuse—and also to seal the fuse casing.

The substances heretofore used almost exclusively for this purpose consisted either mainly of sulphur, the so-called sulphur-cements, or even of pure sulphur, these substances being preferred because they are convenient to handle in the factory and dielectric, but a draw-back to the use of substances of this kind is that, under unfavourable conditions, they may inflame when the fuse is fired and when spread about in burning state they may ignite gas. The tendency in modern mining practice is to increase safety as much as possible.

It is therefore one of the objects of the present invention to reduce the igniting action by the use of non-inflammable or non-combustible substances in electric fuses, for those parts for which a plastic substance, which will subsequently harden, is usually employed.

The invention also contemplates the use, for this purpose, of certain chemical compounds either alone or mixed with one another or with filling substances. The invention also contemplates the combination of the non-inflammable substances with other non-inflammable parts of the fuse, in particular with a non-inflammable insulation for the fuse wires, which insulation may, for example, consist of asbestos or cotton or paper saturated with certain chemicals, which make these materials non-inflammable.

The non-inflammable plastic hardening substances according to the present invention, may consist, for example, of a mastic of cement or of plaster of Paris or of litharge mixed with water-glass, oil, glycerine or water or any two or more of these substances; the litharge may be wholly or partly replaced by precipitated chalk or whitening. The non-inflammable plastic hardening compound may alternatively consist of a casein cement or artificial substances derived from acetyl-cellulose or similar incombustible substances which

can be produced in a condition in which they can be extruded or squirted or cast.

Preferably in carrying out my invention, I employ substances consisting of the higher substituted halogen derivatives of the aliphatic or aromatic hydro-carbons, such as of phenols, or aromatic amines, so far as such compounds are solid fusible substances insoluble in water and have a melting point between 60° and 140° C. These substances may be employed either alone or admixed with one another or with suitable filling substances. The highly brominated and highly fluorinated hydrocarbon compounds are especially suitable, particularly such compounds for instance as:

	Degrees C.
Tetrachlorbenzol—melting point	137 - 138
Trichlorphenol—melting point	67 - 68
Trichloraniline—melting point	67.5 - 96
Tribromophenol—melting point	95
Tribromaniline—melting point	119
Highly chlorinated paraffin and others.	

Inorganic filling materials may be added to the compound, such for example as precipitated chalk or whitening, talc, or asbestos powder. The halogen derivatives of the hydrocarbons may also be mixed with organic substances, such as carnauba wax, Montan wax, cumaron resin and bakelite, thereby producing mixtures ranging from those difficult to ignite to non-inflammable substances which can however be easily moulded or cast.

As an example of the present invention, 100 parts of tribromophenol melted at 100° C. to 120° C. may be mixed with 25 parts of talc and used as the plastic non-inflammable compound.

The chief advantage of the halogen derivatives of the hydrocarbons is their waterproof quality.

By a suitable choice of the constituents of the mass and the method of manufacturing the same, the rate of hardening of the plastic mass can be determined according to requirements, and also the hardness or brittleness after hardening may be kept within desired limits.

So far as the materials are of a porous or hygroscopic nature, this property can be overcome by the mixing of the materials with shellac or other resins, or by the application of a coating of varnish or by floating a waterproof substance over the mass, these additions or coatings being used however in such small quantities as not to create inflammability.

In the accompanying drawings illustrating certain embodiments of the invention, by way of example,

Fig. 1 is a sectional elevation of a fuse of the match-head type having a detonator—or blasting cap—combined therewith.

Figs. 2 and 3 are similar views of a fuse of the match-head type designed to receive a detonator.

10 Fig. 4 is a similar view of a fuse with a loose priming charge, having a detonator combined therewith.

In Fig. 1, the numeral 1 designates a metal shell closed at one end and partly filled with 15 an explosive charge 2. The fuse proper 3 fits tightly within the shell 1 and consists of a small strip 4 of insulating and preferably non-inflammable material, such as impregnated cardboard, to which are attached conductive coatings 5 and 5', say of tinfoil or 20 nickel foil, which are connected by a fine wire. Around the wire and lower ends of the metal foil is a readily ignitable composition which is formed into a match-head 6. The metal foil coatings 5 and 5' are soldered at 10 and 10' to the free or non-insulated ends 7 and 7' of the fuse wires 9 and 9' which are covered by an insulated covering 8 and 8' which is 25 preferably non-inflammable. This fuse proper is held in its position in a tube 12 by 30 a non-inflammable filling 11, for example of casein cement or trichloronaphthaline. Tube 12 tightly fits the shell 1 and is preferably rendered fireproof. The lower end of the 35 tube 12 projects just beyond the match-head 6 so that the fuse proper 3 can be pressed down on to the charge 2 without danger and so that a sufficient distance is maintained between the match-head 6 and the explosive 40 charge to obtain effective action. The shell 1 projects above the tube 12 so as to leave a hollow space which is filled up to the top with a non-combustible mass 13 which may 45 likewise consist of casein cement or any of the substances already mentioned, such as highly chlorinated hydrocarbons. The outer end of the mass 13 and shell 1 is if desired coated with a layer of waterproof varnish 14. A rim 15 on the shell 1 serves to more 50 surely hold the mass 13 in the shell.

In Fig. 2, 16 is a metal tube open at both ends and designed to receive a detonator. In this example, the fuse proper 17, which is of the same construction as that of Fig. 1, is se-

cured in a non-inflammable mass 18, for example, of tribromophenol. In this case, a circular indentation 19 assists in holding the mass 18 in the tube 16.

In Fig. 3, a similar fuse member 17 is secured in the narrower end of a tapering tube 20 of pasteboard, preferably rendered fireproof by suitable impregnation. The fuse member 17 is secured in the shell by a non-inflammable mass 21 which may for example consist of an acetyl-cellulose mass. The shell 20 is adapted to receive a detonator.

In Fig. 4, 22 is a metal shell of a detonator. The fuse proper 23 here consists of two insulated fuse wires 24 and 24' rigidly united at their ends by a cylindrical block 25 of a non-inflammable hardening mass, e. g. cement or the like. The bare or non-insulated ends of the wires project from the block 25 and are connected by a fine wire bridge 26. The block 25 seals one end of a tube 27 which is closed at its other end and is preferably made of non-inflammable material, filled with the loose priming charge 28. That part of the shell 22 which projects beyond the block 25 is filled with a non-inflammable hardening mass 29 which may be similar to that of the block 25 or of any other suitable non-inflammable composition.

In the examples, the use of the invention has been described for fuses having non-inflammable shells and insulation, but the object of the invention, which is to reduce the danger of gas ignition by burning parts of the fuse, can also be attained if the non-inflammable substances are used in conjunction with inflammable fuse parts.

The arrangement of the shell, tubes, wires and leads is not an essential feature of the present invention, nor is it intended that the invention be limited to the examples illustrated.

I claim—

In an electric fuse of the type described, the combination with a non-combustible mass practically enclosing the inflammable fuse parts, of non-inflammable, non-combustible insulation enclosing the fuse-wires, a non-inflammable strip leading to and supporting the ignitable initial charge, conducting coatings covering the sides of said strip, and a conductor between said conducting coatings.

In testimony whereof I affix my signature.

JULIUS SCHÜRMANN.
